CLAIM

The ornamental design for a telescoping automobile door guard, as shown and described.

DESCRIPTION

FIG. 1 is a front elevation view of a telescoping automobile door guard illustrating my new design;

FIG. 2 is a greatly enlarged left end elevation view thereof;

FIG. 3 is a greatly enlarged right end elevation view thereof;

FIG. 4 is an enlarged front elevation view thereof;

FIG. 5 is an enlarged bottom plan view thereof; and

FIG. 6 is an enlarged rear elevation view thereof.
The broken line showing of a portion of an automobile in FIG. 1 of the drawing is for illustrative purposes only and forms no part of the claimed design.
